UNITED STATES PATENT OFFICE.

JAMES McMILLAN, JR., OF PIEDMONT, WEST VIRGINIA.

COMBINED COLLISION MAT AND TORPEDO-DEFLECTING DEVICE.

1,410,820.

Specification of Letters Patent. Patented Mar. 28, 1922.

Application filed September 15, 1921. Serial No. 500,794.

To all whom it may concern:

Be it known that I, JAMES McMILLAN, Jr., a citizen of the United States, residing at Piedmont, in the county of Mineral and

5 State of West Virginia, have invented certain new and useful Improvements in Combined Collision Mats and Torpedo-Deflecting Devices, of which the following is a full, clear, and exact description.

10 My invention relates to means for protecting ships of all types from torpedoes or bombs dropped from air-craft, and has for its object to provide such a device which may be easily raised to protecting position 15 or lowered and stored away as occasion requires.

A further object of the invention is to provide a torpedo deflector which is formed of a plurality of modified collision or battle 20 mats which when not in use as a bomb protector may be employed in the usual manner to stop leaks, etc.

Another object of the invention is to provide extensible means for supporting the 25 torpedo deflector so that the latter will make a very small angle with the vertical and thereby easily deflect falling objects into the water, and also due to its sharp inclination will not affect the firing pin of the bomb or 30 other projectile.

Another object of the invention is the protection of ships from liquid fire and the like, and to this end the collision mats are coated on one side with a non-inflammable substance.

35 Other objects and advantages of the invention will be apparent from the following description when taken in connection with the accompanying drawing, in which,

40 Figure 1 is a side elevation of a ship with my torpedo deflector in place.

Figure 2 is a plan view thereof with a portion of the deflector cut away to more clearly show details.

45 Figure 3 is an enlarged end view of a portion of a ship showing the deflector in position.

Figures 4 and 5 are a side view and plan respectively, of one of the mats, and

50 Figure 6 is a detail view showing one form of means for connecting the mats.

Referring to the drawing more in detail,

the numeral 1 designates a ship to which my novel deflector, indicated generally by the numeral 2, is attached. The deflector 2 is 55 made up of a number of collision mats 3 which are of the usual type except that each mat has woven therein a plurality of steel cables 4 and is coated on one side with a non-inflammable substance. In forming the deflector these mats are connected together by means of links 5 secured to the cables 4, and may be connected at their side edges in any suitable manner.

In order to properly deflect the aerial torpedoes it is necessary that the shield or deflector 2 be set at a very sharp angle with the vertical and I have accordingly provided a plurality of relatively long telescoping masts 6 to which is attached the usual 70 cable 7. On the cable 7 are supported a plurality of pulley blocks 8 through which extend the halyards 9 for raising and lowering the deflector.

On the standards 10 positioned around the 75 deck of the ship are mounted the rollers 11. Over these rollers extend the cables 12 secured to the lower edge of the deflector 2 and anchored to the sides of the ship as shown at 13.

To aid in supporting the deflector the booms 14, pivotally supported at the lower end of the masts, are secured to the deflector at proper intervals.

The deflector is provided with openings 85 15 through which the telescoping stacks 16 may extend in order to carry off the smoke, etc. The deflector is preferably provided with an asbestos covering extending around these openings in order to prevent damage 90 by fire.

In accordance with the patent statutes I have described what I now believe to be the best embodiment of the invention, but I do not wish to be understood thereby as limiting myself or the scope of the invention, as many changes and modifications may be made without departing from the spirit of the invention, all such I aim to include in the scope of the appended claims.

What I claim as new and desire to secure by Letters Patent is:

1. The combination with a ship of telescopic stacks and telescopic masts therefor,

a torpedo deflector, means for securing one edge of the deflector to the sides of the ship, the opposite edge of the deflector being secured to the telescoping masts, and being provided with notches to receive the telescoping stacks.

2. A torpedo deflector comprising a plurality of mats, cables woven in said mats,

and means for connecting cooperating cables in substantial alignment.

3. A torpedo deflector comprising a plurality of collision mats, steel cables woven in said mats, and links for connecting cooperating cables in substantial alignment.

JAMES McMILLAN, JR.
